Inventor
Carl O. Torgerson
by Doug & Hague Att'y's.

UNITED STATES PATENT OFFICE.

CARL O. TORGERSON, OF SLATER, IOWA.

HOG-HOUSE DOOR.

Application filed December 11, 1922. Serial No. 606,155.

To all whom it may concern:

Be it known that I, CARL O. TORGERSON, a citizen of the United States, and a resident of Slater, in the county of Story and State of Iowa, have invented a certain new and useful Hog-House Door, of which the following is a specification.

The object of my invention is to provide a door of simple, durable and inexpensive construction, which may be easily applied to a door opening of a hog house or similar building, so constructed and arranged that when placed in position, the animal may open the door and pass through it, either in or out, and when he has passed through the door, it will automatically close.

More specifically it is the object of my invention to provide a door frame having a door arranged in the frame in such a manner that it will rest normally in a closed position, and provided with means whereby the animal may open the door by engaging the said means with its nose.

These and other objects will be apparent to those skilled in the art.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a side elevation of my improved door and the frame in which it is mounted.

Figure 2 is a side elevation of the same showing the front sides of the door frame removed.

Figure 3 shows a detail transverse, sectional view taken on the line 3—3 of Figure 1.

Figure 4 shows an enlarged, detail, sectional view taken on the line 4—4 of Figure 1.

Figure 5 is a detail bottom and segmental view of the lower and adjacent ends of the doors when in a closed position.

Figure 6 is a detail, sectional view taken on the line 6—6 of Figure 1.

My improved device comprises a frame having a top member 10 and a bottom member 11 and sides 12. Each side of the frame is provided at its upper end with a board 13 which is secured to the frame members 10 and 12 by nails 14, in such a manner that the said boards 13 are spaced apart. The

outer face of the lower edge of each of the boards 13 is provided with a cleat 15 which is also secured in position by means of suitable nails. Each of the side members 12 has each of its side edges provided with a vertically arranged board 16. The upper ends of the boards 16 adjoin the lower edges of the boards 13 and are secured to the cleats 15. The lower ends of the boards 16 are secured to the outer faces of the base members 11. The boards 16 are of a width slightly greater than a fourth of the entire width of the frame, so that an opening 17 is provided between their inner edges.

The member 11 has that portion of each of its outer faces between the boards 16 provided with upwardly extending cleats 18, and so arranged that a groove or channel 19 is provided between them, which is to receive the lower end of the door hereinafter to be described. The outer one of the cleats 18 is provided with a notch 20.

The opening 17 can be of any desired size to allow the animals to pass through it. The door for the opening 17 is formed of two upper pieces 21 and two lower pieces 22, of a thickness slightly less than the thickness of the frame members 10 or less than the space between the boards 13, the width of the boards being slightly greater than half of the width of the opening 17. The upper and adjacent corners of the boards 21 are provided with a hinge 23 mounted in the manner shown in Figure 2, the pivot of the ordinary hinge being withdrawn and a longer one substituted, which is indicated by the numeral 24. The pin 24 is of such length that it will extend through the cleats 15 and the hinge portion. The outer end of the pin 24 may be provided with a nut 25 so that the said pin may be removed whenever it is desired to remove the door. This will permit the two halves of the hinge to separate and the members 21 to be disconnected. The members 21 are so mounted that they may be swung about the pivot 24 from the position shown in Figure 1, to some such position as shown in Figure 2.

It will be seen that the lower edge of each of the members 21, as illustrated in Figure 1, is provided with a horizontal portion and a downwardly and outwardly inclined edge portion 27. The top edge of each of the members 22 is provided with an inclined and horizontal portion to coact with the inclined and horizontal portions of the lower edges

of the members 21. The adjacent and inner ends of the coacting edges are pivoted together by means of a hinge 28 secured in position as illustrated in Figures 1 and 2.

5 The door members 22 are of such length that their lower edges will rest in the groove 19 when the door members are in a closed position. The inner corners of said door members each being beveled outwardly at 29 and each of the beveled surfaces being provided with a plate 30, which are designed to assist in cleaning the groove 19 of loose dirt and trash when the door members are moved from an open to a closed position.

15 The inner face of the left hand door member 22, as shown in Figure 2, is provided with a laterally extending cleat 30^a, while the opposite face of the opposite door member 22 is provided with a laterally extending cleat 31. These cleats provide means for closing the cracks between the adjacent edges of the door members 22 when in a closed position, and also provide means by which the animal is enabled to move the door members 25 to an open position.

Assuming that the door members are in a closed position as shown in Figure 1, with the cleats 31 and 30^a overlapping the adjacent edges of the door members 22 and that 30 the lower edges of the door members 22 are in groove 19, said door members being moved to said closed position by gravity, and that an animal wishes to pass through the door opening, he simply places his nose against 35 the left hand edge of the cleat 31 and moves it sideways toward the right which causes the right hand door member 22 to be swung open a slight distance, and a crack will be formed between the two door members 10 through which the animal will thrust his head and crowd between the door members causing them to be swung apart to a position shown in Figure 2. As soon as he has 45 passed through, the door members will again automatically close, and while they are being moved to their closed positions, the beveled faces 29 of the door member 22 will engage any dirt or foreign matter that has collected in the groove 19 and move it inwardly toward the center of the groove and then thrust it out through the notch 20 of the cleat 18.

By forming the lower edges of the member 21 inclined and the upper edges of the member 22 inclined to coact therewith, I have provided means whereby the doors 22 will be, to a certain extent, balanced in such a manner that the lower ends of the doors 22 will not swing inwardly too abruptly. This, I 55 have found, would hinder the door from assuming a closed position. The amount of this bevel will have to be somewhat regulated according to the weight and dimensions of the doors, which is best determined 60 by actual experiment.

It will be seen in practical operation, that the doors may be mounted in the frame and assembled at the factory ready for use, and the device being comparatively thin, it may be packed and shipped in a minimum amount 70 of space and needs but little crating. The door frame may then be mounted adjacent to the outer and inner face of the frame of any door opening, or one edge of the frame of my improved door may be provided with 75 hinges and the entire frame moved to an open or closed position if so desired, as it is sometimes desirable to place the door frame in the lower portion of a larger door opening, such as a large barn door.

It will be seen that considerable change may be made in the detail construction of my improved door without departing from the spirit of my invention.

I claim as my invention:

1. A door frame, a wall member for each side of said door frame, said wall members being spaced apart and each provided with a door opening, said openings being opposite each other, a pair of upper door members secured together at the upper and adjacent corners by a single pivot, a lower door member pivoted to the lower and inner corner of each of said upper door members arranged to move to a closed position by gravity, a laterally extending cleat for the inner edge of each of said lower door members, said door members being mounted between the wall members of said frame.

2. A door frame having a door opening, a pair of upper door members for said opening, means for pivoting the upper and adjacent corners of said door members together so their lower ends may be free to swing from each other, a lower door member pivoted to the upper inner corner of each of said upper door members and means secured to one of the faces of each of said door members so arranged that the door members may be moved to an open position by being engaged by an animal's nose.

3. A door frame having a door opening, a pair of upper door members for said opening, means for pivoting the upper and adjacent corners of said door members together so their lower ends may be free to swing from each other, a lower door member pivoted to the lower inner corner of each of said upper door members, a cleat secured to the inner edge of each of said lower door members designed to be engaged by an animal's nose so that one of the door members may be moved to a partially opened position to provide a crack between the door members through which the animal may crowd himself, and means for guiding the door members against lateral movement as they are being opened and closed.

4. A door frame having inner and outer wall members spaced apart and each provid-

- ed with a door opening, the lower edge of the said door opening being provided with cleats to form a groove, one of said cleats having at its central portion a notch, door members mounted between the said wall members having their inner and adjacent edges arranged vertically and centrally between the sides of said openings, the upper ends of the adjacent edges of said door members mounted between the said wall members having their inner and adjacent edges arranged vertically and centrally between the sides of said openings, the upper ends of the adjacent edges of said door members being pivoted, each of the adjacent edges of said door members being provided with an outwardly extending cleat and their lower corners provided with a beveled portion, the doors being of such length that their lower ends will travel in the groove formed by the upwardly extending cleats when the door is in a closed position.
5. A door frame having a door opening, a pair of upper door members for said opening, means for pivoting the upper and adjacent corners of said door members so that their adjacent edges will rest together, and so that their lower ends may be free to swing from each other, the lower edges of each of said door members being inclined downwardly and outwardly when said door members are in a closed position, a lower door member pivoted to the lower inner corner of each of said upper door members, said lower door members being provided with 30 upwardly and inwardly inclined edges to fit adjacent to the edges of said upper door members when in a closed position, means secured to one of said lower door members designed to be engaged by an animal's nose 35 for moving the same to a partially open position.
6. A door frame having a substantially rectangular door opening, the bottom side of said door opening being provided with a 40 central longitudinal groove in its upper surface, the said groove having at its central portion a communicating notch of the same depth as the said groove, the door opening being provided with door members pivoted to swing toward and from each other, and to have their lower edges mounted in said groove, the said door members and said groove being so arranged that as the door members are swung toward each other to assume a closed position, that any dirt or foreign substances collecting in said groove will be discharged through the communicating notch.

Des Moines, Iowa, December 4, 1922.

CARL O. TORGERSON.
